HUGO HOFMANN, OF JOHNSON CITY, TENNESSEE, ASSIGNOR TO AMERICAN BEMBERG CORPORATION, OF NEW YORK, N. Y.

TYING STRING FOR SKEINS

Application filed May 14, 1930. Serial No. 452,494.

This invention relates to skeins of thread, more particularly to skeins of freshly-spun artificial yarns, etc., and a particular object of the present invention is to provide means whereby the subsequent handling of freshly-spun yarns is facilitated.

Hitherto, when the filaments of artificial silk have issued from the spinneret, they have been wound directly into skeins, and these skeins, after an intermediate washing or washing and oiling step, either sold as skeins or rewound upon swifts and onto bobbins. Several disadvantages were noted, as for example, the difficulty presented in determining just which way the skein of yarn was wound as it issued from the spinning machine. During the intermediate treatment, the yarn skeins are usually twisted and moved into positions which make it difficult to determine at once which portion of the skein was inside, and which was outside when the yarn was removed from the collector at the spinning machine. Furthermore, when the skeins are placed on swifts preliminary to winding onto bobbins, it was impossible to tell, definitely, just which way the skein would unwind. Ordinarily, the girl operating the swifts straightens out the skeins to the best of her ability, and then places them upon the swifts. Many times, the skein is so placed that it unrolls in the wrong direction, and this necessitates the removal and rearrangement of the swift before the winding may be continued. This method of trial results in many broken threads, the danger of breaking the thread on the swift on either side of the one the operator is working on when the swift must be moved, and the further danger of tangling and breaking the thread when the winding is half completed. This last danger arises from the fact that there is no way by which the operator may tell which is the inside, and which the outside of the skein. The length of the inner windings is, of course, less than that of the outer windings of the skein, and, if the skein is placed on the swift in the wrong position, the inner windings will be wound onto the bobbin first, the larger outer windings then being looser, will tend to "belly" out and be-

come tangled, and also tend to catch on the swift on either side.

It is an object of my invention to do away with this uncertainty as to which is the correct position for the skeins upon the swifts.

A further object is to provide an indicating means which is positive in action, and yet utilizes only the lacing usually used in holding the skeins together.

A further object is to so lace the skein that others, purchasing the skeins, may tell just what position the yarn should occupy on their swifts.

A further object is to so indicate the correct position that subsequent or intermediate wet handling of the yarn will not in any way change the indication. This last object is particularly desirable in the artificial silk industry, since the filaments being treated and often wet, have intermediate wet handling such as washing and oiling, and therefore present difficulties not experienced in handling other yarns, such as, for example, natural silk. In lacing skeins of freshly-extruded filaments a length of string is passed a plurality of times thru the filaments and tied. Later, after any necessary intermediate handling, the skein is placed on the swift, and this string is cut and removed. In the event that there is no indication of the correct position to be occupied upon the swifts, and as to which is the inner and which the outer face of the skeins, the operator tries the skein in one position and then, if she happens to have guessed wrong, removes the skein and replaces it correctly. Even after this removal and replacement there is no way to tell whether or not the shorter side of the skein is outward. Extensive tests in my laboratory and plant have indicated that fully two thirds of the time the skein is placed on the swift in an incorrect position.

In my invention I utilize the ordinary length of string usually used in order to secure the skein together. This string is ordinarily colored or dyed to indicate the denier of the yarn in the skein. This length of string, though, is usually all dyed the same color. In my invention, this length is dyed in such a manner that a portion of the string

remains colorless. When the operator who laces the skeins receives them from the frames above the spinneret he laces them so that the colored end of the string is at the front, and the knot is on the right hand side of the skein.

5 All of the skeins are laced in the same way, and thus the operator who subsequently received the skeins for rewinding, etc., always knows that if the skein is held so that the colored portion of the string is on the outside, and the knot is to the right the skein will be in proper position for winding, twisting, etc.

10 With the foregoing objects outlined, and other objects which will later appear, a representation of the invention is illustrated in 15 the accompanying drawing, in which:

Figure 1 discloses a skein of yarn tied with my new yarn,

20 Fig. 2 shows the position of the skein on the swift, showing how the new tie string indicates the correct position of the skein on the 25 swift; and

Figure 3 is a view of the string used.

30 In the drawings 1 designates a skein of yarn that has just been collected and tied, the tie string being indicated by the numeral 2. The knot of the tie string 3 is at the righthand side of the skein. Other ordinary tie strings 4 and 5 may be used if the size of the skein warrants 35 it. After being treated by washing, oiling, etc., the skein is placed on a swift 6, composed of a hub and several arms 7. The operator in placing the skein upon the swift is careful to place the skein in such a position that the colored portion of the string is outward, and the knot 3 is at the right. In Figure 3 I show 40 a view of a length of string as used in my process. The major portion of the string is colored by some dye, the coloring indicating the denier or size of the filaments composing the yarn. One end of the string, however, is 45 white, and it is this end that the operator tying the skeins leaves on the inside of the skein. In operation, the skeins are removed 50 from the collectors above the spinnerets, tied so that the colored portion of the string is on the outside, and the knot is at the right, and then treated in any usual wet treatment. Because 55 the tie string used is the ordinary tie string with certain special characteristics, there is no danger of losing the string, or having it misplaced or moved during the washing, oiling, etc., steps. After any needed wet treatment the skeins are brought to the 60 operator of the swifts for re-winding upon bobbins, etc. The operator shakes the skein a few times to straighten it out, glances at the string, and, holding the skein so that the colored portion of the string is outermost, and the knot is to the right, places the skein 65 upon the swift. When in this position it is arranged just as it was received from the collector, and no subsequent replacement or rearrangement is necessary.

65 The foregoing illustration of the use of my

new device is to be taken as illustrative only, as it is apparent that various changes may be made in the construction disclosed without departing from the spirit of the invention.

I claim:

70 1. The method which consists in tying around a supported skein of artificial filaments a flexible marking member, consisting of only two portions, joined to each other, and each having a distinctive individual characteristic, so that the knot appears to the right of the person tying said member, and part of a predetermined one of said portions, adjacent the point of junction, appears on the upper face of the skein.

75 2. The method which consists in tying around a supported skein of artificial filaments a flexible marking member consisting of two portions possessing distinctive color characteristics and joined one to the other, so that the knot appears to the right of a person tying said member, and part of a predetermined one of said colored portions, adjacent the point of junction, appears on the upper face of the skein.

80 3. The method of handling artificial fibres which consists in winding such fibres onto supports in uniformly arranged skeins, placing across each skein one of a number of similar flexible members composed of but two 85 portions, each with a distinctively individual characteristic, and tying the flexible members in such manner that all of the knots are at the same edges of the respective skeins, the points of meeting of the distinctive portions are at the opposite edges, and similar parts adjacent said points appear on the outer parts of the skeins.

90 4. The method of handling fibres which consists in winding such fibres onto supports 95 in uniformly arranged skeins, placing across each skein one of a number of similar flexible members composed of but two portions, each portion possessing its own color characteristic, and tying the flexible members in 100 such a manner that all of the knots are at the same edge of the respective skeins, the points of meeting of the distinctive portions being at the opposite edges, and similar parts adjacent said points appear on the outer parts 105 of the skeins.

110 5. The combination of a skein of artificial fibres and means to indicate the unwinding direction of the same, said means comprising a flexible member tied across the skein 115 and consisting of two distinctively individual portions only, said flexible member being so arranged that the knot is at one predetermined edge of the skein, the point of meeting of the portions is at the opposite edge, and a part of a predetermined one of the portions, adjacent said point of meeting, appears on the outside of the skein.

120 6. The combination of a skein of artificial fibres and means to indicate the unwinding 125

direction of the same, said means comprising a flexible member tied across the skein and composed of two distinctively colored portions only, said flexible member being so arranged that the knot is at one predetermined edge of the skein, the point of meeting of the two colored portions is at the opposite edge, and part of a predetermined one of the colored portions, adjacent said point of meeting, appears on the outer surface of the skein.

In testimony whereof I affix my signature.

DR. HUGO HOFMANN.
